UNITED STATES PATENT OFFICE

2,161,393

BLOOD PRESSURE CUFF

James P. Tye, Albany, Ga.

Application September 19, 1938, Serial No. 230,698

4 Claims. (Cl. 128—327)

My invention relates to cuffs such as are used in apparatus for taking a patient's blood pressure.

Heretofore it has been the general practice to provide a cuff comprising a fabric body wide at one end and tapering toward the other end, the wide end having a pocket to receive a suitable inflatable air bag which is connected by a flexible tube with a manometer or other suitable pressure indicator, and is designed for inflation through a second tube connected with an air pump (rubber-bulb-type or other suitable kind). These cuffs are wound around the patient's limb (usually the arm), commencing with the larger end, and the narrower end is finally tucked under a previous convolution. The air bag is then inflated to provide the necessary pressure on the arteries to give the required readings of the instrument, after which the physician (or nurse) releases the tucked-under end of the cuff and unwinds it from the patient's limb. He usually rolls the cuff into a small bundle and replaces it in a case in which the whole instrument is carried.

The cuff now in common use, just referred to, often gets stringy, particularly when used on large arms.

My invention, therefore, has for its object to provide a cuff which will retain its shape (i. e., not stretch out of shape and become stringy) and will also automatically unroll itself from the patient's limb into a small bundle which can be readily carried in the instrument case.

Generically, my new and improved cuff comprises three portions arranged end to end in a unitary structure, one end portion comprising a pocket for the inflatable bag, the other end portion comprising a narrow tongue to facilitate turning it under to hold the cuff against loosening under inflation stresses, and the middle portion comprising a reinforced main body having means provided for continuously tending to roll up the tongue and main body upon releasing the cuff and thereby automatically removing it from the patient's limb and making the cuff ready to be put away in the case.

Other objects will in part be obvious and in part be pointed out hereinafter.

To the attainment of the aforesaid objects and ends the invention still further resides in the novel details of construction, combination and arrangement of parts, all of which will be first fully described in the following detailed description and then be particularly pointed out in the appended claims, reference being had to the accompanying drawing, in which:

Fig. 1 is a perspective view (parts being broken away) of my new and improved cuff opened up, by pulling in opposite directions on the tongues 9 and 11.

Fig. 2 is an enlarged detail plan view (parts broken away) to show more clearly the main or middle portion of the cuff.

Fig. 3 is an enlarged detail longitudinal section on the line 3—3 of Fig. 2.

Fig. 4 is an enlarged detail cross section on the line 4—4 of Fig. 2.

Fig. 5 is an enlarged detail section on the line 5—5 of Fig. 2.

Fig. 6 is a perspective view showing how the cuff, when released, automatically rolls up.

In the drawing, in which like numerals and letters of reference indicate like parts throughout, 1 is the larger end of the cuff which is made as a pocket to contain the inflatable bag 13, the pocket 1 having side openings 2 and 3 respectively for the tubes 4 and 5, one of which goes to the usual pump (not shown) and the other of which goes to the usual indicating instrument (not shown). The portion 1 of the cuff is preferably of the same width throughout its length and formed (as is also the middle portion 10 and the tongue 11) by folding over the piece of fabric C and sewing it together along the free longitudinal edge by a suitable seam 6. The outer end is closed in part by stitches 8, the material being turned in and sewn by stitches 7.

The tongue portion 11 and the middle portion 10 have the longitudinal edge sewn together by a concealed line of stitches C'. Other methods of sewing the doubled-over cloth C, which forms the cuff, may be employed as desired.

The middle portion 10 tapers from the end portion 1 to the tongue 11 and is reinforced by a strip of fabric 14 into which is woven a set of flat coil springs 16 which pass through slits 15 in the strip 14 as best shown in Figs. 2 and 3. The springs 16 are secured to the strip 14 by suitable means, as for example by staples 17. The strip 14 is sewed in place by rows of stitches 18 passing through the cloth C and strip 14; as shown by the arrows a in Figs. 1 and 6, the natural tendency of the springs is to roll up the cuff in the direction indicated.

The outer end of the portion 1 is provided with an edge opening the width of the tongue 9, through which opening the inflatable bag 13 may be inserted or removed. When the cuff is in place on the arm, the tongue 9 is tucked into the pocket over the adjacent edge of the bag 13 and

prevents it from blowing out of the hole (see dotted lines, Fig. 6).

In applying the cuff, the portion 1 is placed on the arm and the remainder of the cuff wound around the arm in the direction of the arrow b in Fig. 1, i. e., in a direction opposite that in which the springs 16 function, with the tongue 11 tucked under at the end of the wind. When tongue 11 is released, springs 16 will at once wind up the intermediate part (see Fig. 6) with tongue 11 inside, and thus automatically unwind the cuff from the patient's arm. Then, by simply folding portion 1 around the roll in Fig. 6, the cuff will be ready for storing in a small space.

My cuff can be applied more quickly and more perfectly to, and removed more easily and quickly from the patient's arm than can the old-style cuff.

From the foregoing description, taken in connection with the accompanying drawing, it is thought that the construction, method of use and advantages of the invention will be clear to those skilled in the art and I wish it understood that, while I have shown a preferred embodiment of the invention—one that has been in successful use for some time—changes in the details of construction can readily be made by those familiar with the art, without departing from the invention and within the scope of the appended claims.

What I claim is:

1. A blood pressure cuff comprising two end portions and an intermediate portion, one end

portion constituting a pocket and the other end portion constituting a tongue, and ribbon-spring means in said cuff for rolling it into a bundle automatically.

2. A blood pressure cuff comprising two end portions and an intermediate portion, one end portion constituting a pocket and the other end portion constituting a tongue, combined with means continuously tending to roll up the cuff, said means comprising ribbon springs secured within and extending longitudinally of the cuff, means to anchor the springs with said intermediate portion, said anchoring means comprising a strip of flexible material into which the springs are laced, and means for attaching said springs to said strip.

3. A blood pressure cuff comprising two end portions and an intermediate portion, one end portion constituting a pocket and the other end portion constituting a tongue, and means for flexibly reinforcing said intermediate section and continuously tending to roll up the same.

4. A blood pressure cuff, comprising an elongated bandage having a pocket at one end to receive an inflatable bag and having a tongue at the other end, combined with means disposed in the bandage between said pocket and said tongue continuously tending, when released after the cuff has been wound on a patient's limb in a predetermined way, to release the cuff from the limb and in doing so to assume the form of a roll.

JAMES P. TYE.
